Primary Examiner — Messina L Smith*Assistant Examiner* — Jillian Mazzola(74) *Attorney, Agent, or Firm* — Suiter Swantz pc llo(57) **CLAIM**

The ornamental design for a toolbox, as shown and described.

DESCRIPTION

FIG. 1 is a perspective view of a toolbox showing our new design;

FIG. 2 is a top plan view thereof;

FIG. 3 is a front elevation view thereof;

FIG. 4 is a right side elevation view thereof;

FIG. 5 is a rear elevation view thereof;

FIG. 6 is a left side elevation view thereof; and,

FIG. 7 is a bottom plan view thereof.

The broken lines shown in the drawings depict portions of the toolbox that form no part of the claimed design.
